UNITED STATES PATENT OFFICE.

ASA CUSHMAN, OF PROVIDENCE, RHODE ISLAND, ASSIGNOR TO OREN C. DEVEREUX, OF SAME PLACE.

SEPARABLE BUTTON.

SPECIFICATION forming part of Letters Patent No. 434,177, dated August 12, 1890.

Application filed June 14, 1890. Serial No. 355,507. (No model.)

To all whom it may concern:

Be it known that I, ASA CUSHMAN, a citizen of the United States, residing at Providence, in the State of Rhode Island, have invented a new and useful Improvement in Studs, of which the following is a specification.

My invention consists in the improved construction and arrangements of the parts of the stud, as hereinafter fully set forth.

10 Figure 1 represents a side elevation of the stud. Fig. 2 represents the head and post in elevation and the shoe in central section, taken in the plane $x x$ of Fig. 3. Fig. 3 represents a plan view of the shoe with the perforated front plate removed to show the internal mechanism of the shoe. Figs. 4 and 5 represent plan views of the opposite catches of the shoe. Fig. 6 represents an edge view of the catch shown in Fig. 5.

20 In the accompanying drawings, A represents the head of the stud; B, the post, provided at its lower end with the annular groove a , which is adapted for engagement with the catches C C' of the shoe. The shoe 25 D is formed of the plate b, which is struck up with a rim f, the supporting-plate c, which is struck up with the raised posts d d', which serve to support the front plate e, the several parts being secured together by turning over 30 the edge of the rim f. The plate c is also provided with a perforation g, adapted to receive the lower end h of the post B.

The catches C C' are each provided with a semicircular recess i, adapted to clasp the 35 post B within the annular groove a, and with

the opening j adapted to receive the end of the spring k, the catch C being also provided with a tooth l, while the opposite catch C' is provided with a recess m, adapted to receive the said tooth, the said catches being adapted for a limited opposite turning movement upon the struck-up posts d d, which also serve to support the front plate e, having a central perforation r. The catches C C' are also provided with an arm n, which projects outwardly through an elongated opening o in the rim f. When the post B is in locked engagement with the catches C C', by pressing the projecting arms n n of the catches C C' toward each other the inner ends of the catches will be thrown apart, so as to release the post B, and thereafter the said catches will be brought back to their original closed position by the resilience of the spring j.

I claim as my invention—

The combination, with the head A and post B, of the shoe D, provided with the plate b, having a perforated rim f, the centrally-perforated supporting-plate c, provided with the posts d d, the catches C C', turning upon the posts d d, and provided the one with a recess m and the other with a tooth l, adapted to enter the recess, and with an arm n projecting through the perforation in the rim, the spring j, and the centrally-perforated front plate e, substantially as described.

ASA CUSHMAN.
